(57) **CLAIM**

The ornamental design for an instrument, as shown and
described.

DESCRIPTION

The patent file contains at least one drawing executed in
color. Copies of this patent with a color drawing will be
provided by the Office upon request and payment of the
necessary fee.

FIG. 1 is a perspective view of an instrument showing a first
embodiment of our new and ornamental design;

FIG. 2 is an alternate perspective view thereof;

FIG. 3 is an alternate perspective view thereof;

FIG. 4 is an alternate perspective view thereof;

FIG. 5 is a rear elevation view thereof;

FIG. 6 is a front elevation view thereof;

FIG. 7 is a side elevation view thereof;

FIG. 8 is a side elevation view thereof;

FIG. 9 is a top plan view thereof;

FIG. 10 is a perspective view of an instrument showing a
second embodiment of our new and ornamental design;

FIG. 11 is an alternate perspective view thereof;

FIG. 12 is an alternate perspective view thereof;

FIG. 13 is an alternate perspective view thereof;

FIG. 14 is a rear elevation view thereof;

(Continued)

FIG. 15 is a front elevation view thereof;
 FIG. 16 is a side elevation view thereof;
 FIG. 17 is a side elevation view thereof;
 FIG. 18 is a top plan view thereof;
 FIG. 19 is a perspective view of an instrument showing a third embodiment of our new and ornamental design;
 FIG. 20 is an alternate perspective view thereof;
 FIG. 21 is an alternate perspective view thereof;
 FIG. 22 is an alternate perspective view thereof;
 FIG. 23 is a rear elevation view thereof;
 FIG. 24 is a front elevation view thereof;
 FIG. 25 is a side elevation view thereof;
 FIG. 26 is a side elevation view thereof; and,
 FIG. 27 is a top plan view thereof.
 The broken lines are for the purpose of illustrating portions of the instrument that form no part of the claimed design.
